UNITED STATES PATENT OFFICE.

CHARLES P. STEVENS, OF SAN PEDRO, AND WILLIAM S. MORRISSEY, OF LOS ANGELES, CALIFORNIA, ASSIGNORS OF ONE-THIRD TO JOHN R. EVANS, OF LOS ANGELES, CALIFORNIA.

DESIGN FOR AN AUTOMOBILE BODY.

Application filed March 10, 1925. Serial No. 12,675. Term of patent 14 years.

To all whom it may concern:

Be it known that we, CHARLES P. STEVENS and WILLIAM S. MORRISSEY, citizens of the United States of America, residing at San Pedro and Los Angeles, respectively, in the county of Los Angeles and State of California, have invented a new, original, and ornamental Design for Automobile Bodies, of which the following is a specification, reference being had to the accompanying drawing, forming part thereof.

Figure 1 is a side elevation of the automobile body, showing our new design.

Fig. 2 is a plan view thereof.

We claim:

The ornamental design for an automobile body, as shown.

WILLIAM S. MORRISSEY.
